GAME BOARD

Alvie D. Nix, Horatio, Ark. 71842

Substituted for abandoned design application Ser. No. 25,086, Sept. 21, 1970. This application Jan. 23, 1973, Ser. No. 326,010

Term of patent 14 years

Int. Cl. D21—01

U.S. Cl. D34—5 SS

FIG. 1

FIG. 2

FIG. 1 is a perspective view of a game board showing by new design; and,

FIG. 2 is a top plan view of the same on a somewhat enlarged scale.

The characteristic feature of my design resides in the particular multi-lines pattern printed on the board in combination with the cruciform game pathway as shown.

I claim:

The ornamental design for a game board, as shown and described.
